US00D850859S

(12) **United States Design Patent** (10) **Patent No.:** **US D850,859 S**
Chen (45) **Date of Patent:** **** Jun. 11, 2019**

(54) **STAND**

- (71) Applicant: **Tiff's Treats Holdings, Inc.**, Austin, TX (US)
- (72) Inventor: **Leon Chen**, Austin, TX (US)
- (73) Assignee: **Tiff's Treats Holding, Inc.**, Austin, TX (US)
- (**) Term: **15 Years**

(21) Appl. No.: **29/606,643**(22) Filed: **Jun. 6, 2017**

(51) LOC (11) Cl. **07-01**
 (52) U.S. Cl. **USPC D7/558**

(58) **Field of Classification Search**

Primary Examiner — Derrick E Holland*Assistant Examiner* — Andrew Kerr(74) *Attorney, Agent, or Firm* — Norton Rose Fulbright
US LLP(57) **CLAIM**

The ornamental design for a stand, as shown and described.

DESCRIPTION

FIG. 1 is a front view of a stand showing my new design, the back view being identical;

FIG. 2 is a right side view thereof, the left side view being identical; and,

FIG. 3 is a top view thereof.

The broken lines showing portions in FIGS. 1 and 2 are for the purpose of illustrating environmental structure and form no part of the claimed design.
